COMPOSITE LANTERN-SLIDE.

1,111,635.

Specification of Letters Patent.

Patented Sept. 22, 1914.

Application filed July 7, 1913. Serial No. 777,747.

To all whom it may concern:

Be it known that I, SYDNEY B. AUSTIN, citizen of the United States, residing at Baltimore, Maryland, have invented certain new and useful Improvements in Composite Lantern-Slides, of which the following is a specification.

My invention relates to lantern slides of the composite type, in which a picture carrying member and a screen member are associated with each other and have relative movement so as to expose the picture sections at the open spaces between the lines of the screen; and it concerns particularly the means whereby the picture and screen members are held together and are permitted to have the relative movement mentioned.

The invention consists in the features and combination and arrangement of parts hereinafter described and particularly pointed out in the claims.

In the accompanying drawings, Figure 1 represents a front view of my invention; Fig. 2 a rear view; Fig. 3 a top view; Fig. 25 4 an end view, and Fig. 5 a sectional view along the line 5—5 of Fig. 1. Figs. 6 and 7 are opposite side views of a modification; Fig. 6^a is a detail of Fig. 6; Figs. 8 and 9 are horizontal sections, and Fig. 10 a vertical section.

In carrying out my invention I provide a two-part casing or holder, making up an open frame, or in other words, a frame open at its center to expose at this point the transparent members of the composite slide so as to permit the light to shine through for displaying the picture. While this holder may assume various forms, in the particular construction which I have chosen to illustrate my invention, it consists of a main frame member 1, in the form of a frame open at its center and having upper and lower strips or bars 2 and end bars 3. At the corners of this frame portions are cut out and the edges at these cut out points are turned laterally at 4 to provide lugs to engage the end or vertical edges of one of the members of the composite slide, this member being indicated at 5. These lugs 4 are four in number and engage the vertical edges of the member 5 at or near the top and bottom thereof. The member 5 is thus held at an intermediate point with relation to the length of the main member 1, and the ends

of this main member which extend beyond these points are extended laterally and then longitudinally of the main member and parallel therewith, as indicated at 6, thus forming at the ends of the main member guideways in which the other member of the holder may be reciprocated, these guideways being indicated at 7. The supplemental or movable member of the holder is indicated at 8, this consisting of top and bottom longitudinally extending strips or bars 9 connected by the vertical bars or strips 10, the said vertical bars at their upper and lower portions having lugs or flanges turned laterally as at 11, to engage the ends of said edges of the movable member of the composite slide indicated at 12. The upper and lower bars of this movable member have flanges or lugs extending laterally therefrom over and under respectively the upper and lower edges of the member 12 of the composite slide, these flanges or lugs being indicated at 13, and by this construction it will be seen that the member 12 is held against displacement either vertically or horizontally in relation to the supplemental or movable holding member 8. The main member 1 of the frame or holder also has a horizontal flange 13' at its lower edge, and by this the member 5 of the composite slide is held against vertical displacement, and the flanges 13 on the supplemental member 8 by reaching over the upper edge of the slide member 12 also serve to prevent vertical displacement of this slide member in relation to the other transparent slide member 5. The two members 1 and 8 of the holder or frame are held against displacement vertically by fingers or clips 14 of the main holding member 1 reaching up over and down on the rear side of the movable frame member 8. By the construction described above it will be clear that the two transparent members 5 and 12 of the composite slide are held accurately in relation to each other in one direction so that there will be no displacement in this direction, namely, vertically, while at the same time these transparent members will be permitted relative movement in a horizontal direction.

It will be understood that the use of the terms horizontal and vertical is for convenience of description, as I do not limit myself to a horizontal movement of one

slide member in relation to the other, as movement in other directions may be provided for. The feature I desire to make clear is that the transparent members of the composite slide will be held accurately against movement or displacement in one direction while permitting relative movement in another direction for the purpose of getting the motion picture effect. In order to move one of the frame members relatively to the other various means may be employed. In the particular construction shown, however, this means includes lugs or projections 16 extending up from the supplemental frame member and having screws 17 adjustably mounted therein to be borne upon or engaged with any suitable operating mechanism on the display apparatus in which the holder with its composite slide is placed and operated. The slide may be placed at the display point by hand or it may be brought to the display point automatically, and when at said display point in either case the operating means will be such as to give the members of the composite slide the desired relative movement. I prefer to make the holder of sheet metal bent up as shown and described above, though I do not limit myself in this respect. It will be observed that the two transparent members of the composite slide are not connected with each other except through the intermediary of the members of the holder or frame.

In operation one frame member with its transparent slide member moves in relation to the other frame member which is attached to the second transparent slide member. The slide members are held accurately and positively in proper relation and are guided accurately in their movements. The holding lugs or flanges of the frame can be bent back to take out one composite slide and place another in position. No special formation of the transparent or glass slide members is necessary in order to render them capable of moving one on the other, nor is it necessary to directly attach to them lugs or other operating devices.

While I have referred to the device above described as a lantern slide it will be understood that I make such reference as being one aspect of my invention. I do not wish to indicate that its use is limited to a lantern or similar apparatus. Where I refer to a composite picture it will be understood that this term is descriptive of any composite device to be displayed by bringing different portions thereof to view through the screen.

The screen and picture member may be connected by flexible pieces at the end to insure their proper alinement while allowing one to move in one direction or the other. These flexible pieces may be omitted.

In Figs. 6 to 10 I show a modification in

which, like in the form first described, two metal frames are employed, one slidable on the other, and each carrying one of the glass members of the composite picture slide. The outer frame 1' has portion 6' overlapping 70 the inner frame 8'. The glass 5' is held to the outer frame by lugs 4' which are struck out from the frame and bent across the edge of the glass member 5'. Projections 11' on the inner frame member 8' extend over the 75 end edges of the glass member 12'. The glasses and frames are held against vertical displacement by the flanges 13' and lugs 14'. The hollow projections 16' are formed by bending the metal clips over upon themselves and securing the lapped portions together by striking out a tongue on one which passes through an opening on the other, or a rivet may be used as at 18.

I claim:—

1. A display device comprising two transparent members, one a screen member and the other a composite picture carrying member, and a holder consisting of two centrally open frames, each holding one of the transparent members, said frames having relative movement in one direction and held against movement in other directions to present the different parts of the picture member to the clear spaces of the screen. 95

2. A display device comprising a transparent screen member and a transparent composite picture carrying member, and a holder consisting of two open frames one carrying the screen member and the other carrying the picture member, said frames being guided to have relative movement in one direction, one of said frames having means whereby it is moved in relation to the other, substantially as described. 100

3. A display device comprising a transparent screen member and a transparent composite picture carrying member and a holder consisting of two open frames, one carrying the screen member and the other carrying the picture member, said frames being guided to have relative movement in one direction, one of said frames having means whereby it is moved in relation to the other, said means consisting of a projecting portion of one member to be engaged by automatically operating means, substantially as described. 110

4. A display device comprising transparent screen and picture members, an open frame for each member attached thereto, one of said frames being guided on the other to move one transparent member in one direction relative to the other substantially as described. 120

5. A display device comprising transparent screen and picture carrying members, an open frame attached to each, said open frames being attached together to be handled as one body, and movable one on the other in 130

- one direction but held against movement in other directions.
6. A display device comprising transparent screen and picture carrying members, an open frame attached to each, said open frames being attached together to be handled as one body and movable one on the other in one direction but held against movement in other directions, one of said frames having engaging portions by which it may be moved automatically when the device is placed in a display apparatus.
7. A display device comprising a composite slide made up of transparent picture and screen carrying members, a holder for said members open at front and back and consisting of two members slideable one in relation to the other.
8. A display device consisting of a transparent picture carrying member and a screen member, a frame attached to each, one frame being slidably mounted on the other and means projecting from the edge of one frame for operating the slide, substantially as described.
9. A display device consisting of a transparent picture carrying member, and a transparent screen member, a frame for each member, each of said frames being open at the center and engaging the edge of its transparent member, said transparent members being held between the frame members one of which latter is slideable on the other, substantially as described.
10. A display device comprising transparent picture carrying and screen members, an open frame for each fitting against the face margin of the transparent members and having lugs or flanges at the edge engaging the edges of said members, one frame member having portions extending over the edge of the other frame member to guide the latter thereon in its movement, substantially as described.
11. A display device comprising transparent picture and screen members, a frame for each fitting against the face margins thereof at back and front and having lugs or flanges engaging the edges of the transparent members, said frames holding the transparent plates between them and one having guides at top and bottom for slidably holding the other frame member, one of said frames having end guides engaging the other frame, substantially as described.
12. A display device consisting of a transparent screen member, a picture carrying member, a frame for each member, each having laterally extending portions to engage the member to be held thereby, one of said frames being connected to and guided on the other whereby the screen and picture members may be relatively displaced, substantially as described.
13. In combination the two glass members, one a picture carrying member and the other a screen carrying member, a metal frame for each member attached thereto, one frame being slideable on the other to thereby display different portions of the picture member through the screen, substantially as described.
14. A lantern slide comprising a screen member and a picture carrying member, a frame for each of said members, one slideable in the other, the movable frame having an extension for operating it, substantially as described.
15. A lantern slide comprising a transparent screen member, a transparent picture carrying member, one slideable in relation to the other, a pair of frames inclosing said members, the fixed member being held by one of said frames, substantially as described.

In testimony whereof, I affix my signature in presence of two witnesses.

SYDNEY B. AUSTIN.
